RAILWAY RAPID TRANSIT CAR BODY

William M. Schmidt, Harper Woods, Mich., assignor to
Pullman Incorporated, Chicago, Ill., a corporation of
Delaware

Filed Aug. 12, 1964, Ser. No. 81,257

Term of patent 14 years

(Cl. D66—1)

FIG. 1 is a perspective view of a railway rapid transit car body showing my new design;

FIG. 2 is a front end elevation thereof;

FIG. 3 is a side elevational view of the car body opposite that shown in FIG. 1, but showing only the front portion of the car body; and

FIG. 4 is a plan view of the front portion of the car body.

The essential feature of my design resides in the portion shown in full lines.

I claim:

The ornamental design for a railway rapid transit car body, substantially as shown and described.
